UNITED STATES PATENT OFFICE.

CLEMENT DORSEY, OF COSHOCOTON, OHIO.

DESIGN FOR A FLY-PAPER SHEET.

SPECIFICATION forming part of Design No. 20,691, dated April 28, 1891.

Application filed March 23, 1891. Serial No. 386,158. Term of patent 7 years.

To all whom it may concern:

Be it known that I, CLEMENT DORSEY, a citizen of the United States, residing at Coshocton, in the county of Coshocton and State of Ohio, have invented and produced a new and original Design for Fly-Paper, of which the following is a specification.

The figure is a plan view of my design.

The leading feature of my design is a sheet containing advertising-spaces having a rectangular or central portion provided with a roughened or mottled surface. In addition to this feature I provide a border consisting of an ornamental strip, on which I represent a number of flies going toward the central portion of the sheet.

A designates the main central portion of the sheet having the mottled surface.

C designates the inside border-line; D, the outside border line. Across the space between these two lines extend transverse lines E E, forming squares in the border. In each of these squares is a circle F, and on each circle is a fly G G, headed toward the center of the sheet. This makes a neat catchy design and an ornamental as well as valuable article of commerce.

What I claim is—

The design for a fly-paper sheet as herein shown and described.

In testimony whereof I affix my signature in the presence of two witnesses.

CLEMENT DORSEY.
